Patented Jan. 24, 1922.

UNITED STATES PATENT OFFICE.

MAX MENDELSON, OF NEW YORK, N. Y.

FOLDING CHAIR.

1,404,537.

Specification of Letters Patent. Patented Jan. 24, 1922.

Application filed April 13, 1921. Serial No. 461,023.

To all whom it may concern:

Be it known that I, MAX MENDELSON, a citizen of the Republic of Russia, residing at New York city, in the county of New York and State of New York, have invented certain new and useful Improvements in Folding Chairs, of which the following is a specification.

This invention relates to improvements in folding chairs in which two pairs of pivotally joined supports or legs are capable of collapsing so as to fold a divided seat into substantial alignment with the legs.

The object of this invention is to provide an efficiently operating device of this character, wherein the members may be folded to occupy a small space.

A further object of this invention is to provide suitable supporting elements for a divided seat member, whereby the latter is prevented from accidentally collapsing while in its extended position.

The invention consists in the structural features and combinations of parts fully described, with reference to the accompanying drawing, wherein—

Fig. 1, is a perspective view of the folding chair with parts shown broken away to disclose the angle guides and the connecting link.

Fig. 2, is a substantially cross sectional view through the chair in its extended position.

Fig. 3, is a view similar to that shown in Fig. 2, except that the chair is in its folded position.

Fig. 4, is a detail perspective on an enlarged scale showing the connecting link between the oppositely extending angle pieces of the seat.

Referring to the drawing 10 and 11 denote the two pairs of supporting legs, said legs being preferably constructed of flat metal stock. The legs of each pair cross each other at 12 where they are pivoted together. This construction provides a substantially X shaped supporting structure for a divided seat 13. The legs of each pair are connected to the opposite legs near their lower ends by means of tie-bars 14. The upper ends of the two pairs of legs are connected by guide rods 15 and 16. The guide rods 15 and 16 are in substantially the same plane with each other throughout all of their movements.

The seat 13 comprises forward and rear-

ward sections 19 and 20 respectively, said sections being each provided with angle pieces 21 secured to the underside of the sections adjacent their side edges. Each angle piece 21 has a slotted depending flange 22, the slots of the flanges on each seat section being opposite and parallel to each other. The opposite parallel slots in the flanges 22 of the forward section 19 are adapted to receive the guide rod 15; and the opposite parallel slots in the flanges 22 of the rearward section 20 are adapted to receive the guide rod 16. Stop lugs 23 are carried by the under face of angle pieces 21 and are located adjacent the inner end of each flange 22. These lugs 23 are in the path of movement of the guide rods 15 and 16.

Pivots connected to the inner ends of the flanges 22 is a substantially T shaped link 24 provided with pivot pins 25 and 26 about which said angle pieces turn. The stem of the T shaped link 24 is bent inwardly at right angles to the body of said link to provide a flange 24a which underlies and supports the abutting inner edges of the sections of the seat 13 when the latter is in its extended position. Intermediate the length of the link 24 and beneath the flange 24a is a third pivot pin 27 which receives one end of a supporting brace 28. The opposite end of the brace 28 is pivoted on a pivot pin 29 carried by the forward member of the pair of legs. The supporting brace 28 is disposed at an angle when the seat is in extended position and supports the link 24 against downward pressure by establishing a triangular truss between the link 24 and two points on the forward leg of the chair. The upper end of the brace 28 is cut away slightly to receive the inner lower corner of the flange 22 carried by the forward section 19. Weight applied to the seat will bring this corner member into contact with the cut away portion of 28 so that a rigid support for the seat 13 may be established. In order that the downward pressure may be equalized a supporting brace 28 is provided on each side of the chair.

The operation of folding this chair will be best understood with reference to Figs. 2 and 3, in connection with the following description. To fold the chair to its closed position it is simply necessary to cause the legs of each pair to swing towards one another about the pivots 12. By this operation the seat sections will move rearwardly as a unit and in a hori-

zontal plane and the guide rod 16 will traverse the length of the slot 22 until the stop lug 23 is engaged, whereupon, the distance between the guide rod 15 and the connecting link 24 has shortened sufficiently to compel the section to swing about the guide rod 16 and pivot pin 25 until the lower edge of the slotted portion of the angle piece engages the rear edge of the brace 28. The movement of 10 the section 20 is then completed and the guide rod 15 has traversed its guide slots 22 substantially half of its length permitting the section 19 to remain horizontal. The final movement of the guide rod 15 towards the 15 link 24 raises the latter slightly due to the acute angle of the brace 28 and the constant diminishing distance between rod 15 and the pivot pin 25. As the rod 15 swings towards the rod 16 the section 19 turns about 15 and the lower edge of the slotted portion of the angle piece 21 engages the forward edge of the brace 28. The sections 19 and 20 will, when completely folded as shown in Fig. 3, be in substantial parallel relation to the legs. 20 25 When the chair is in its extended position and weight is applied to the seat 13, there will be a tendency for the central portion to sag. But due to the peculiar construction of the T shaped connecting link 24 the adjacent 30 inner edges of the sections 19 and 20 are supported upon flange 24^a of the link 24. To further support the seat 13 the inclined supporting braces 28 tend to force the members of each pair of legs further apart. This exerts an outward pull at the ends of the sections 19 and 20 and which pull will aid in maintaining the seat in a horizontal position when the latter is extended.

I claim:

- 40 1. A folding chair, comprising pairs of pivotally interconnected legs, a sectional seat supported by said legs, links pivotally connecting the inner ends of said sections together, and means supporting said links 45 which when said legs are collapsed the sections of said seat will first move rearwardly as a unit and will thereafter move towards each other about opposite ends of said links to lie parallel to said legs.
- 50 2. A folding chair, comprising pairs of pivotally interconnected legs, a sectional seat

supported by said legs and comprising forward and rearward sections pivotally linked together, and means whereby when said legs are collapsed the seat will be first moved rearwardly substantially the length of the rearward section and then the sections will move toward each other to lie in substantial parallel relation with the legs. 55

3. A folding chair, comprising parallel 60 pairs of crossed legs pivotally interconnected together, guide rods connecting the upper ends of parallel legs, a sectional seat comprising forward and rearward sections pivotally linked together, slotted parallel flanges carried by each section and adapted to receive said guide rods, and means supporting the central portion of said seat when the latter is in extended position and moving the seat as a unit towards the rear when the legs are 65 collapsed so as to cause the guide rods to traverse the length of the slotted flanges whereupon the sections will move toward each other about the guide rods to fold into substantial parallel relation with the legs. 70 75

4. A folding chair, comprising pairs of pivotally interconnected legs, a sectional seat supported by said legs and comprising forward and rearward sections, a T shaped link pivotally connecting the inner edges of said 80 sections and provided with a supporting flange adapted to receive the abutting edges of the sections when the latter are in extended position, and means pivotally connecting the T shaped link with one leg so that downward pressure on said seat will tend to further separate the legs. 85

5. A folding chair, comprising parallel pairs of pivotally interconnected legs, guide rods connecting the upper ends of each pair 90 of legs, a sectional seat provided with parallel slotted flanges adapted to receive said guide rods, lugs carried by said seat and located in the path of movement of said guide rods, and means whereby when the legs are 95 collapsed, the sections will first move rearwardly until the lugs are engaged by the guide rods and will thereafter move towards each other about said guide rods to lie parallel to said legs. 100

In testimony whereof I affix my signature.
MAX MENDELSON.
